(57) **CLAIM**

The ornamental design for a display panel for forklift, as shown and described.

DESCRIPTION

FIG. 1 is a perspective view of a display panel for a forklift showing our new design;

FIG. 2 is a front elevation view thereof;

FIG. 3 is a rear elevation view thereof.

FIG. 4 is a top plan view thereof.

FIG. 5 is a bottom plan view thereof.

FIG. 6 is a left side elevation view thereof.

FIG. 7 is a right side elevation view thereof.

FIG. 8 is a referential front view showing energization condition thereof; and,

FIG. 9 is a referential view showing use thereof.

The portion of the article shown in broken lines in FIG. 8 and the steering wheel shown in broken lines in FIG. 9 are shown for illustrative purpose only and forms no part of the claimed design.
